ALBERT A. E. STERZING, OF NEW YORK, N. Y.

DYNAMO-ELECTRIC MACHINE.

1,299,053.

Specification of Letters Patent.

Patented Apr. 1, 1919.

Application filed March 25, 1914. Serial No. 827,043.

To all whom it may concern:

Be it known that I, ALBERT A. E. STERZING, INC., a subject of the King of Great Britain, and a resident of the city, county, and State of New York, have invented certain new and useful Improvements in Dynamo-Electric Machines, of which the following is a specification.

This invention relates generally to machines working on the principle of magneto-electric induction, and particularly to those wherein the electric current is caused to flow continuously in the same direction.

Primarily, the invention has for its object to produce an improved machine of this character composed of but a few simple parts, easily constructed and readily assembled, and forming together a structure distinguished by its strength, compactness, thorough efficiency, and economical operation.

A secondary object is to provide for the machine a field-magnet unencumbered with the usual polar fittings and yet capable of yielding a copious supply of lines of force evenly distributed throughout.

A further object is to combine with the said field-magnet a symmetrical armature which is correctly balanced electrically as well as in mechanical respects, and has a large effective area compared with the diameter of the magnetic shell housing the same.

Another object is so to construct, proportion, and mount the said armature as to enable it to perform its work within a relatively narrow gap between the polar surfaces of the field-magnet, and at the same time to provide it with adequate means of ventilation, so that while there will be no diminution in the weight of the metal to interfere materially with the magnetic flux, the armature will be kept sufficiently cool always to prevent generation of excessive heat therein with consequent resistance and waste of energy.

Still another object is to equip the armature with a novel set or series of conveyers, distributors, conductors, and collectors of electric current which are adapted conjointly to lead, gather, and transmit the current constantly in the one direction through the shortest practicable path from the negative to the positive elements of the machine, thereby avoiding reversals, insuring an ample electrical output in a brief

period of time, and so favoring the production of current that, being given the requisite conditions for the development of electromotive force, namely, an abundant magnetic flow, a reliable wire-winding, and the rapid cutting of lines of force, the machine may be depended on to operate successfully at a high voltage.

Other objects and advantages of the invention will be readily perceived upon perusal of the descriptive matter hereinafter incorporated.

With the said objects in view, the invention consists of the new and improved elements, combinations, subcombinations, and arrangement of parts herein shown and described in their preferred embodiment, especial reference being made to the characteristic features thereof presently to be outlined and further set out in the subjoined claims.

Among other peculiar features thereto appertaining, this invention includes an annular field-magnet hollowed out from its inner circumference to form two continuous surfaces of opposed polarity affording an intervening gap adapted to receive the rim of a discoidal armature.

A subsidiary feature of the invention consists in making the field-magnet relatively massive in the region of the polar surfaces, on opposite sides thereof, where the armature revolves.

Another feature relating to the field-magnet resides in the winding of the magnetic wire-coils within the same in planes parallel to that of the armature, on opposite sides of the latter.

According to another feature of the invention, the rim of the armature is equipped laterally with current conductors consisting of short sections of wire specially formed for close juxtaposition at their inner ends, but separated from one another at their outer ends to provide air gaps therebetween.

The same element, in accordance with still another feature of the invention, carries an unbroken equipment of current conductors shaped so as to preclude interspacing.

Other features of the invention pertain to the ventilation of both the field-magnet and the discoidal armature, to the current collectors and transmitters, and to certain structural details, all of which will be easily identified as the specification proceeds.

The preferred mode of construction and operation of the machine will now be de-

scribed with reference to the drawings here-to annexed, wherein—

Figure 1 is a vertical cross-section of a substantially complete dynamo-electric machine embodying one form of the present invention;

Fig. 2 is a side elevation of the same, partly broken and partly in section;

Fig. 3 is a cross-section showing a detail 10 pertaining to an electric terminal located circumferentially in the middle vertical plane of the machine;

Figs. 4 and 5 are detached side views of bare conductors seen in side elevation on the 15 sections of armature represented by Figs. 6 and 7, respectively;

Fig. 6 is a fragmentary view, illustrating the armature as provided with single layers of current conductors;

Fig. 7 is a similar view, showing the armature equipped with conductors disposed in 20 double layers;

Figs. 8 and 9 are rear or exterior views 25 of similarly positioned halves of concentric annular brushes that are provided on the opposite sides of the armature;

Fig. 10 is a peripheral view of the segment of outer brush shown in Fig. 8, looking downward from the upper edge thereof;

Fig. 11 shows in diametrical transverse 30 section the segment of inner brush represented by Fig. 9, as it appears looking up inside the same; and

Fig. 12 is a side elevation of the armature denuded of its wire equipment, save 35 two small segments thereof, which are shown respectively covered with current conductors of the two different forms before mentioned,

In the form herein shown, the body of this 40 improved machine consists of two annular iron castings 21, 22, which are duplicates one of the other, and therefore can be made conveniently from a single pattern. These castings, as seen in Fig. 1, are substantially 45 U-shaped in cross-section, though they are held up sidewise, with their closed, convex ends turned oppositely outward, and consequently with their sides, which are of different lengths, also in opposed relation. The 50 longer sides are made to abut edgewise against each other as at 23, on a median line of the machine, at which place the opposed parts are provided with paired lugs 24, adapted to receive cross-bolts 25 between 55 them, by means of which the two castings are secured firmly together. The shorter sides terminate each at some distance from the middle line 23, leaving a gap 26 between them, which communicates with the vacant 60 spaces or recesses 27 that are inclosed within the conjoined pair of U-shaped castings. Thus constructed and assembled, the paired castings 21 and 22 constitute a magnetic shell or field-magnet substantially in the 65 form of a hollow ring which is open longitudinally throughout its inner circumference, and the concave portion of which affords a circular channel wherein a disk-armature (hereinafter described) is adapted to rotate.

In the dynamo-electric machine of the form herein set forth, the field-magnet is meant to be the stationary member, and therefore the said annular castings are supported by and rest upon four legs 28, located 70 as usual on opposite sides of the machine. These supports 28 may be produced integral with the field-magnet, and fastened in any approved manner to the floor or base upon which the machine is set up for operation. 80 Figs. 1 and 2. No special foundation need be provided for the aforesaid field-magnet, nor does it require any framing, as its constituent parts are sufficiently heavy and well-poised to stand alone, and besides they are 85 so united as to brace each other.

It is intended that the said annular field-magnet should be relatively powerful, and for that reason it is made rather massive, particularly in the inner peripheral part 90 thereof, which is quite thick and compact, compared with its outer circumferential portion, as shown in Fig. 1. The special object aimed at is to provide in the vicinity of the armature a magnetic element of suitable permeability, capable of generating a bounteous supply of lines of force streaming in a continuous current. The heavier mass of the iron, it will be observed, borders the 95 gap 26, the sides of which are designed to afford continuous polar surfaces. The sides of the gap, characterized each by width and continuity, form a large magnetic field for the armature, and being massive, they afford the requisite depth of polar areas without the addition of such pole pieces, cores, or extensions as are ordinarily employed.

The gap 26 and recesses 27 communicate 100 with one another inside the field-magnet and together constitute one continuous annular opening, which is T-shaped transversely and the vertical part of which (as seen in Fig. 1) presents a relatively narrow space for the projecting rim of the armature, while the horizontal portion forms coupled compartments by the sides of the latter, that are partly utilized for the reception of magnetic wire-coils 31. These coils may be laid 110 conveniently in annular channels 32, at the bottom of their respective compartments, as the 115 said Fig. 1 shows. The coils 31, it will be noted, are placed in their channels 32, in planes concentric with the axis of the field-magnet or magnetic shell, and parallel to the plane of the armature, on opposite sides 120 of the same. Provision is thus made for wiring the field-magnet in proximity to the poles thereof. It is understood that the flow of magnetic lines of force should be brought 125 up to and maintained at the correct density 130

between the poles of the field-magnet here the rim of the armature is revolving, that there may not be undesirable fluctuations, nor eddies, in the electric current, but, on the contrary, to insure at all times a continuous current of uniform strength, capable of developing steadily the desired degree of electromotive force.

Centrally of its circumferential part, and directly opposite the edge of the armature within the same, the field-magnet is provided with a series of transverse slots 36, which communicate with the aforementioned recesses 27 and gap 26, and thus afford a means of ventilation for the interior of the magnetic shell and the inclosed armature. These slots, preferably, are made to cross the middle plane of the combined field-magnet and armature, at regular intervals between the lugs and bolts that unite the two iron castings 21 and 22. Being elongate and narrow, they do not impair the activity of the iron, nor permit too great a disturbance of the air that passes through the T-shaped opening (26, 27), no matter how fast or how slow the armature is revolved. The slotted outer part of the field-magnet, it will be observed, has little if any weight to carry, and therefore it may be made as thin as is consistent with the structural strength of the machine, since there is a sufficiently good magnetic conductivity provided, otherwise, due to the position of the armature in the circuit.

In accordance with common practice, the machine herein described, when used as a generator, will be supplied with an exciting current from the outside, which may be derived from any convenient source.

By preference, the armature is of the disk type, as previously mentioned, and it constitutes the rotary member in the exemplification of the invention herein expounded. The body of this armature, in the form represented by Figs. 1, 2, 6 and 7, comprises two distinct parts, to wit, a solid hub-and-web portion 41, and a radially-perforated portion 42. As shown, these parts may be cast integrally together, and they are mounted so as to turn in a vertical plane, on a horizontal shaft 43, to which they are keyed, either to rotate the same or to be revolved thereby, depending on the function eventually discharged by the machine, that is, whether it be that of a generator, or motor, or converter. In any event, the body of the armature and its shaft connection are made sufficiently substantial and durable to resist properly the effects of both the turning moment and the centrifugal force which they will have to withstand, whether they be formed integral or composed of two or more pieces rigidly interconnected.

Standards 45, with bearings 46 at their upper ends, are placed one at each side of

the field-magnet, to support the said shaft and armature thereon. The shaft is passed through and across the annular field-magnet, so that it coincides with the transverse axis of the magnetic field, while the armature is mounted so as to revolve centrally therein, with its rim projecting into the T-shaped opening composed of the before-mentioned gap 26 and recesses 27, where the magnetic lines of force are taken up by the armature on lines parallel with the field's axis, but in a peripheral plane. The standards 45 are located close to the sides of the field-magnet, and consequently that part of the shaft 43 which extends between the bearings 46, and carries the armature, is short and not liable to flexure. Moreover, a pair of collars 47 is provided on the same part of the shaft, which collars abut against the inner sides of the bearings 46 and coöperate in maintaining the shaft rigid, besides preventing endplay thereof transversely of the machine. The collars 47 are held on the shaft by means of set-screws 48, which latter admit of the shaft being longitudinally adjusted, in such a way as to center exactly the armature within the field-magnet and bring it into perfect electrical as well as statical balance, assuming, of course, there has been a symmetrical distribution of the armature wires all around the shaft, in the manner about to be described. No difficulty will be experienced in alining the shaft or keeping it in line, owing to its separable bearings and standards, which are secured in place independently of the field-magnet's supports. The standards are sufficiently narrow, as shown by dotted lines in Fig. 2, to offer practically no obstacle to reaching the interior of the field-magnet when it becomes necessary to effect there-in some slight repair of the inside parts. Both standards or either of them may be quickly removed, also, if desired, to afford full access to the internal parts and give the machine a general overhauling.

The rim of the armature is preferably made of cast-steel or soft iron, and forms the core of a special equipment of copper wires, designed to replace the ordinary armature windings, to wit, the current-conductors thereto belonging. These wires are disposed in two lateral series, respectively designated herein by the reference numerals 51 and 52. They are, of course, furnished with proper insulation, as indicated at 53, and have their terminals on opposite sides of the armature's rim. This annular portion (rim 42) of the armature is made to traverse clear across the gap 26 in the field-magnet, extending outwardly into the recesses 27, and inwardly to a plane more or less closely circumscribing the inner periphery of the united annular U-shaped castings 21, 22. As the polar surfaces of the field-magnet bordering the gap 26 are of fair width and the rim of

the armature has still larger superficial dimensions, a good flow of magnetic lines of force is continuously supplied, to be cut by the conductors 51 and 52 revolving with the armature. The construction, it will be noted, permits the use of very powerful poles and an armature of commensurate capacity with in a magnetic shell of comparatively small diameter and to that extent is favorable to 10 the rapid and economic production of an electromotive force intended to furnish the requisite torque with a modicum of electric current.

Short sections only of copper wire are 15 needed for the current conductors 51 and 52. As illustrated in Figs. 1, 2 and 12, the several wires, or wire sections 51, 52, are laid flat against the sides of the armature rim, facing therewith the opposite polar 20 faces of the field-magnet, within the gap 26. The inner ends of all these wires are made to adjoin one another near the inner edge of the rim 42, from which they are separated by rings 54, of brass or other non-magnetic 25 metal, recessed therein (Fig. 1). At their outer ends, the wires are also isolated from the armature by similar non-magnetic rings 55, likewise embedded laterally in the outer edge of the rim. The latter-named ends of 30 the wires, however, may or may not be placed close together. In the smaller-sized machines, it is deemed preferable to have the outer ends of both series of wires 51 and 52 spaced apart to provide air-gaps 56 be- 35 tween them, as seen within the broken portion of Fig. 2 and in the upper part of Fig. 12. In the larger machines, on the other hand, it is preferred to have the outer ends of the said wires 51, 52, nearer to one another, 40 as shown at the bottom of Fig. 12. The opposite ends of the wires are respectively soldered to rings 61, 62, 63 and 64, hereinafter described. The soldering should be effected while the wires are under tension, that is, 45 held taut with the aid of pliers or some other suitable tool. When the wires are being applied to the latter-named rings, the interstices caused by the removal of the insulation from the several wires at the fastening 50 points thereof are filled with solder, which is shaved off to present a smooth surface on each side of the rim 42, as will be understood.

Figs. 4 and 5 illustrate what are considered 55 the two best shapes of wire to apply on armatures of all sizes, dividing the latter into large and small, respectively. Both forms of wire shown, it will be observed, are gradually flattened and correspondingly ex- 60 panded in opposite directions a greater or less distance from their upper portions down to their lower ends. The wire represented by Fig. 4 is thus made flat and spread from the point marked 57, thereby enabling 65 a number of like wires to be placed side by

side, with their flattened portions directed edgewise against the armature, in such a manner that the several wires will be adjacent to one another at the inner edge of the rim, but will have the intervening air-gaps 70 56 at the outer edge thereof, as before noted with reference to Fig. 1 and to the top part of Fig. 12. The wire of Fig. 5 is similarly flattened and expanded from a higher point, 75 58, and consequently thinned down more, so that when a number of such wires are positioned with the attenuated edges thereof against the sides of an armature rim having a large circumference, their outer ends, as well as their inner ones, come close to one 80 another in the manner represented in the bottom part of Fig. 12, as previously stated.

This is believed to be the most practicable mode of construction and arrangement to adopt for the current conductors on the armature, where the density or compactness of the copper wire equipment becomes a desirable factor or an important consideration. Wires of this improved manufacture can be laid in practically perfect continuity upon 85 both sides of an armature, since the ends of all the wires, because of their peculiar configuration, will naturally lodge side by side on the opposite lateral surfaces of the rim, converging thereon in proper ratio to the 90 diminution of their superficial areas edgewise, and forming an unbroken assemblage on each side of the armature. As best seen in Figs. 6 and 7, the rim 42 is slightly hollowed slantingly from its outer edge inward 100 on both sides, to afford suitable depressions wherein the flat ends of the wire are nested with their expanded edges transversely disposed and projecting outward, so that the 105 sides of the wired rim, which are to face the 110 poles in the gap 26 of the field-magnet, will be substantially straight, whether one or more layers of wire be used, for instance, in either of the ways suggested in the figures last named.

Outwardly, the ends of the two series of wires 51 and 52 are also united by solder to the contiguous sides of two pairs of rings 61, 62, and 63, 64, which perform the functions, respectively, of distributing the current 115 to and collecting it from the aggregate of conductors on the armature. Hence, these two pairs of rings will be referred to herein as current distributors and current collectors. For the purposes of this specification, it will be assumed that the inner rings 61 and 62 are the distributors, and the outer rings 63 and 64 the collectors, of the electric current. The four rings 61—64 may be made of copper, aluminum, or steel, each 120 preferably in one piece. In the form of the invention shown, these rings cover up completely both ends of the two series of wires 51 and 52, on the opposite sides of the armature rim, to which they are secured, as also 125 130

with one another in pairs, by means of brass bolts 65. As Fig. 1 shows, the bolts 65 are sunk at both ends deep into the opposed inner sides of the said pairs of rings, that 5 they may not leave projections on the outer faces thereof, which it is desired to keep smooth throughout for a more extended contact with the brushes hereinafter described. Meanwhile the wires 51 and 52 are securely 10 bound in place and well adapted for the discharge of their function as armature conductors.

Several advantages accrue from the use of 15 the special forms of wire conductors applied to the armature as above described. In the first place, the wires closely embrace the sides of the armature rim, against which they are firmly held by and between the various non-magnetic, and distributing and 20 collecting rings, and mutual fastenings, sufficiently tight to insure and maintain a proper clearance for the wired rim in the gap between the opposed polar surfaces of the field-magnet. The intermediate portions 25 of the comparatively short wires are crowded by the said fastenings toward the body of the armature, on both sides, instead of being pulled off by the magnetic drag prevalent in some other machines. The result is a free, 30 unobstructed field wherein the rim of the armature remains unimpeded while cutting the magnetic lines of force.

Another gain resulting from the employment of the conductors 51 and 52 is found 35 in that only a small amount of copper is actually used for the armature winding or rather covering, on account of the short path afforded to the electric current between the distributor and collector rings. Besides the 40 reduction in the element of cost, by using a less quantity of copper and a larger proportion of iron in the armature, a stronger magnetic field is obtained. The requisite amount of copper is had, as will be understood, by gaging the cross-section of the conductors to suit, and if more is desired for 45 any particular case, one may resort to the expedient of using two or more layers of wire as suggested in Fig. 7; according to the 50 purpose in view.

By disposing the copper wires laterally over the rim of the armature, and locating them between continuous polar surfaces as herein shown, a full working length of the 55 current conductors is obtained within a small compass, and their longitudinal measurement will not vary very much for any size of machine, the circumferential increase of the armature rim calling mostly for a larger 60 number of conductors of the standard length.

The current conductors herein disclosed further permit the grouping together in one compact mass, of several elements which 65 otherwise would be separate and hence would

occupy more space. Thus, the armature's rim or effective core 42, the aggregate of wire conductors 51 and 52 thereon, the two pairs of non-magnetic rings 54, 55, isolating the wire ends from the rim, as also both 70 pairs of current distributors 61, 62 and current collectors 63, 64, over the wire ends, and the web-and-hub portion 41 keyed to the shaft 43, are all united to form a single member, which practically may be considered 75 as the armature, taken as a whole. This construction is possessed of great strength, and enables the armature with its adjuncts or accessories to be lodged as a unit and within limited quarters in the very center 80 of the magnetic field.

In order to guard against more or less objectionable or needless pulsations in the current, the polar surfaces of the field-magnet are divided into obliquely-disposed sections 85 71, produced by grooves 72 and 73. As shown in Fig. 2, the grooves 72 are concentric with the rim of the armature, whereas the grooves 73 run crosswise thereof and are substantially tangential to the armature 90 shaft. Now, if the armature is revolved in either direction, it will be seen that the wires in the series 51 and 52 thereon are positioned angularly with relation to the sides of the sectioned polar surfaces, and consequently 95 will be enabled at all times to snap the lines of force readily, thereby securing a smooth flow of electric current.

A means of ventilation for the armature is incidentally afforded by the above-mentioned grooves 72, 73, which constitute as many avenues of escape for the heat arising from the rapidly revolved armature and accumulating in the gap 26 or about the pairs 100 of rings 61-64. Proper ventilation and 105 cooling of the armature are further provided for by forming the rim 42 thereof with radial passages 74, running inward from a peripheral groove 75 in the outer edge of the rim and curving out alternately toward the 110 opposite sides of the latter, as at 76, 77. See Figs. 1 and 12. The combined passages 74, 75, and gap 26 lead from the center of the machine to the recesses 27 beyond them, and thence out by way of the slots 36, the rapid revolution of the armature's rim causing a fan-like draft therethrough, which carries away the circumambient air and immediately relieves the armature from the incipient heat. 115

The previously mentioned current distributing and collecting rings 61-64, are preferably attached to the rim of the armature so as to rotate with it sidewise. Being secured on the sides of the armature, as shown, 120 they are not subject to any prejudicial action of the centrifugal force developed at the outer edge of the rim. It is deemed advisable to make these rings of soft iron or steel instead of copper. However, they may be 125 130

copper-plated on three sides, which would aid in soldering thereto the ends of the wire conductors 51 and 52. It is intended that all of the wires 51, 52, should have individual contact at their ends with both pairs of these rings, so there will be no neutral wire, and none poorly connected in the circuit. The two pairs of rings, positive and negative respectively, form an integral 10 part of the armature circuit, the electric current being received by them directly from the conductors on the armature and supplied to the external circuit, or the reverse. The said two pairs of rings, it will be noticed, are kept well apart on opposite sides of the machine, where a high insulation can easily be effected.

Annular brushes 81, 82, 83, 84, are placed in sliding contact with the aforesaid rings 20 61, 62, 63, 64, and held laterally thereagainst by certain devices next to be described. Figs. 1, 2, and 8 to 11. By preference, the rear or outer portion of these brushes is made hollow so as to inclose a core 85, as 25 indicated in the sectioned parts of Fig. 11, and their face or inner portion is slotted at various angles transversely to produce therein an endless, circular series of teeth-like projections 86. The core may be of 30 steel, but the dentate shell thereover, formed by the said hollow portion and its said projections, gives best results when made of either copper or aluminum, the latter being preferably copper-plated. It will be seen 35 that the projections 86 are well adapted, by virtue of the induced air-currents during the rotation of the armature, to dissipate rapidly the heat caused by contact of the brush with the adjoining current distributor or 40 current collector, whichever it may be. A brush of this kind can be manufactured cheaply, and therefore may be replaced often at small expense, if it should wear out fast. It is expected, of course, that the toothed 45 shell will become worn sooner than the broader-surfaced distributor or collector ring with which it is to be in frictional engagement, but its relatively low cost admits of more frequent renewals.

50 Like the distributor and collector rings to which they are respectively assigned, the said annular brushes are arranged in pairs, corresponding to the paired rings in size and location. Accordingly, the brushes 81 55 and 82, apportioned to the current distributors 61 and 62, are placed exteriorly thereof within the inner periphery of the annular field-magnet, and the brushes 83, 84, allotted to the current collectors 63, 64, are similarly positioned contiguous thereto inside the recesses or compartments 27 of the castings 21, 22. The two pairs of brushes are suspended, each in its proper vertical plane as illustrated in Fig. 1, by means of a circular series of knobs 91, provided thereon

and engaged by adjusting members 92. The knobs 91 may be of steel or wrought iron and welded or riveted to the aforementioned core 85, Fig. 11. The adjusting members 92 are slideable horizontally in the direction of their length and are disposed in concentric series (Figs. 1 and 2) respectively supported in central frames 93, and in the outlying portions of the U-shaped castings 21, 22. The frames 93 may consist of cast-iron rings, fastened by bolts 94, passing through flanges 95 thereof, to lugs 96, distributed at predetermined points around the inner borders of the field-magnet, on opposite sides of the armature. Bearings 97 are formed 80 at regular intervals transversely of the frames 93, for the inner series of adjusting members, and similar bearings 98, wherein to fit the adjusting members of the outer series, are provided in the sides of said castings.

Each adjusting member aforesaid comprises, as shown, a brass sleeve, numbered 92. The several sleeves are urged inward, against the pairs of rings 61—64 and over the slightly conical knobs 91 thereof, by means of plugs 103 and spiral springs 99, coiled around said sleeves and plugs and anchored at their inner ends, either to one of the frames 93 or to lugs 100 on the sides of the field-magnet, according as the adjusting members belong to the inner or to the outer series. At their outer ends, the said springs are engaged each by two pins 101 and 102, passed transversely through the plug 103, entering the latter from the outer end thereof. These pins pass also across the spirals of the spring, so that either of them can be grasped by the hand and turned either forward or back. Thus, the pins 101 and 102 may be used for advancing or retracting the two series of adjusting members as needed, to make or break contact between the brushes controlled thereby and the corresponding distributor or collector rings. A few convolutions of the springs 99 are placed under compression between these two pins, so that the latter may not be shifted along the spirals of the former, through vibration of the brushes 83, 84. The compressed part of each spring will thus have practically the effect of a lock-nut on the corresponding adjusting member, and the several springs, which obviously are subjected to less tension at the top than at the bottom of the machine owing to unequal distribution of the weight of the suspended brushes, can all be adjusted to meet the various requirements.

As indicated at the upper right-hand corner of Fig. 1, iron disks 106 may be employed in order to balance the paired brushes 81, 83, and 82, 84, which are suspended from the inner ends of the sleeves 92 by the knobs 91. These disks or counterweights 106 are 130

adapted to ride loosely on the compressed coils of the spiral springs 99, between the pins 101 and 102 of the plugs 103, a recess 107 in each disk allowing the pin 101 to be 5 engaged by the spirals of the spring therein when it is desired to regulate the tension of the latter for the purpose before mentioned.

Tension springs 111 may be substituted for the counterweights 106 above described, 0 if desired. As shown at the lower left-hand corner of Fig. 1, springs of this type could be attached by one end in grooves 112, around outwardly-projecting portions of the plugs 103, and similarly secured at the other 15 end to some fixed part of the machine. Such springs would be preferable to the counterweights for all motors designed for purposes of travel, for instance, those operating cars or vehicles of various descriptions, on rail- 20 ways, tramways, speedways, etc.

It is now apparent that, arranged as described and shown, the several adjusting members can be manipulated so as to bring the appropriate degree of pressure to bear 25 on the brushes and the contacting rings 61—64, and insure their smooth operation. A perfect control is provided over the individual brushes, and by adjusting them so as to press evenly always upon the thereto 30 related rings, the wear will be equalized, no sparking will occur, and the distortion of the brushes commonly due to the cutting of ruts or hollows therein by unequal friction will be avoided.

35 As illustrated in Figs. 1 and 2, the inner brushes are joined in the electric circuit by wires 115, lodged and soldered in the semi-circular or C-shaped pockets 116, provided on the outside of each brush, between the 40 knobs 91 thereof. The wires 115 are thence doubled up, led to, and attached to copper rods or wire cables 117, 118, located one on each side of the machine. These rods form each an open circle on the opposite sides of 45 the field-magnet, from which they are supported by brass staples or eye-screws 119. They constitute the negative terminals in the machine shown, and are suitably connected with the main wires of the electric circuit. 50 The said wires are given a relatively large contact with the inner brushes, for the purpose of distributing the electric current quickly, as well as evenly. Separate wires like these are preferred to a direct connection of the said terminals with the inner brushes. The terminal rods 117, 118, it will be understood, have each one "dead" end, and are wired to or in the external circuit in such a way that all the induced electro- 55 motive forces are caused to act in the same direction. These two rods or wire cables are united at some distance from the machine, to constitute the regular negative section of the circuit, which is divided simply 60 for the purpose of placing therein the two

brushes that are in contact with the inner pair of rings on the opposite sides of the armature.

A third rod or cable 121, of same metal and form as the rods or cables 117, 118, above 70 referred to, constitutes the positive terminal in the particular species of machine represented in the accompanying drawings. This last named terminal rod is preferably, located so as to encircle the field-magnet, 75 centrally thereof, in the manner brought out by Figs. 1, 2, and 3. Outwardly grooved insulators 122, provided at various intervals on some of the paired lugs 24, afford the proper support for the rod 121, which is 80 further secured in position by the wiring 123, as indicated in Fig. 3. Electrical connection between the positive terminal and the outer brushes 83, 84, is effected by means of a series of short wires 126, each soldered 85 centrally of its length in a groove 127, formed around these brushes (Figs. 1 and 10). The wires 126 are thence led outwardly to the rod 121, first by crossing the ends of adjacent wires, and then passing the 90 crossed ends thereof through alternate slots of the series 36, in the middle circumferential plane of the field-magnet.

The herein described invention in its broader aspects is not limited to the precise construction set forth and illustrated, nor to any particular construction by which the same has been or may be carried into effect, as many changes may be made in the details without departing from the main principles 95 of the invention or sacrificing its chief advantages.

Having now described my invention, what I claim, and desire to secure by Letters Patent of the United States, is:

105

1. A dynamo-electric machine comprising a hollow annular field-magnet having relatively massive inner portions and thinner outer portions, magnetic coils intermediate of said inner and outer portions, a laterally wired discoidal armature mounted in said field-magnet with its rim projecting outwardly between the massive parts thereof beyond said coils, and axially extending brushes engaging the projecting portion of 110 said armature.

2. A dynamo-electric machine comprising a hollow annular field-magnet composed of longitudinally divided halves having relatively massive portions held apart and thinner portions joined together around the same, magnetic coils placed adjacent to said massive portions, a laterally wired discoidal armature constructed so as to make it project past said coils and bring its rim into a space 115 intermediate of said divided halves, and axially extending brushes engaging the projecting portion of said armature.

3. A dynamo-electric machine comprising an annular field-magnet having bare polar 120

125

120

130

- surfaces of substantially equal magnitude opposed one to the other, a discoidal armature with a rim carrying series of wires radially disposed between said surfaces, 5 magnetic wire coils surrounding the field-magnet laterally of said armature rim, and axially extending brushes engaging the armature transversely of said wire series.
4. A dynamo-electric machine comprising 10 a hollow field-magnet of annular form composed of similar halves joined centrally together at the periphery, magnetic wire coils wound interiorly around said field-magnet on opposite sides of its central joint, a discoidal armature mounted in the field-magnet with its rim projecting beyond said coils 15 into a gap between said halves, and axially extending brushes engaging the projecting portion of said armature rim.
- 20 5. A dynamo-electric machine comprising a field-magnet of annular form longitudinally divided, and having internal recesses in opposite sides, magnetic wire coils laid in said recesses, and a discoidal armature with 25 a rim carrying groups of separate wires projecting outward in planes intermediate of said wire coils.
6. A dynamo-electric machine comprising an annular field-magnet composed of longitudinally divided halves united in a middle 30 plane, channels encircling the same at substantially equal distances from the dividing line thereof, magnetic wire coils in said channels, and a discoidal armature having 35 a rim covered with separate wires centrally located within the field-magnet.
7. A dynamo-electric machine comprising an annular field-magnet hollowed out laterally from its inner circumference, oppositely located channels formed inside of said 40 field-magnet, a laterally wired discoidal armature projecting into the hollow of the field-magnet midway between said channels, magnetic wire coils in the latter positioned 45 within the periphery of said armature, and axially extending brushes having peripheral engagement with the armature beyond said coils.
8. A dynamo-electric machine comprising 50 an annular field-magnet hollowed out from its inner circumference to form a gap extending outwardly therefrom and a recess transverse to the same, said gap and recess forming together an opening substantially 55 T-shaped in the field magnet's cross-section, oppositely located channels formed within said recess, a discoidal armature projecting through said gap, groups of separate wires radially disposed on both sides of said armature, magnetic wire coils wound annularly about the field-magnet in said channels, and axially extending brushes engaging the projecting portion of the armature.
9. A dynamo-electric machine comprising 60 a field-magnet having transverse circumfer-

entially arranged slots and opposed continuous polar surfaces sectioned by intersecting grooves communicating with said slots, combined with a radially-wired discoidal armature mounted to revolve between said polar 70 surfaces with its rim directed edgewise relatively to said slots and sidewise with relation to said grooves.

10. A dynamo-electric machine comprising an annular field-magnet hollowed out 75 from its inner circumference to provide opposed polar surfaces with a gap therebetween, grooves sectioning said surfaces on opposite sides of said gap, and outwardly-leading passages communicating with both 80 gap and grooves, combined with a laterally-wired discoidal armature arranged to revolve with the opposite sides of its rim facing the polar surfaces within the length of said passages.

85 11. A dynamo-electric machine comprising an annular field-magnet formed with opposed polar surfaces and a circular series of parallel ventilating passages disposed in a diametrical direction, combined with a 90 discoidal armature having radial slots in communication with said passages and electrically wired on opposite sides of its said slots.

12. A dynamo-electric machine comprising 95 an annular field-magnet hollowed out from its inner circumference to provide opposite poles and formed with transverse circumferential passages suitable for diametrical ventilation, combined with a discoidal armature between said poles having a rim provided with radial slots in communication with said passages, said slots leading outwardly through said rim from opposite sides of the armature.

100 13. A dynamo-electric machine comprising an annular field-magnet having opposed polar surfaces with a gap therebetween, and a discoidal armature formed with radial 110 passageways and mounted to revolve in said gap, the rim of said armature being peripherally grooved lengthwise and wired on opposite sides of the groove therein.

14. In a dynamo-electric machine, a discoidal armature formed with a longitudinal 115 groove around its periphery and with radial slots in its rim leading to said groove, combined with electrical wiring laid upon said rim, on opposite sides of the peripheral groove and radial slots.

120 15. In a dynamo-electric machine, a discoidal armature, and wires thereon formed with converging flat ends lying edgewise on the opposite sides of said rim.

16. A dynamo-electric machine comprising 125 a field-magnet having poles of annular form, a discoidal armature arranged to revolve with its rim projected between said poles, the latter being sectioned superficially by intersecting grooves respectively concen- 130

tric with and tangential to the hub of the armature, and wires on the rim of the armature substantially radial to said hub.

17. A dynamo-electric machine comprising an annular field-magnet, a centrally uncovered discoidal armature mounted therein, current conductors laterally disposed on the rim of said armature, concentric distributor and collector rings on both sides of the 10 armature contiguous to the ends of said conductors, and correspondingly positioned brushes held in contact with said rings on opposite sides of the machine.

18. A dynamo-electric machine comprising an annular field-magnet, a centrally uncovered discoidal armature mounted therein, distributor and collector rings carried concentrically on opposite sides of the armature, current conductors on the armature's 20 rim having their ends connected each with one of said rings respectively, and oppositely located annular brushes held in contact with the several rings.

19. A dynamo-electric machine comprising a field-magnet, a discoidal armature therein, current conductors disposed laterally on the armature's rim, current distributors and current collectors connected with the ends of said conductors, brushes held in 30 contact with said distributors and said collectors, and means for effecting individual adjustment of said brushes.

20. A dynamo-electric machine comprising an annular field-magnet, a discoidal armature mounted to revolve therein, said armature being centrally uncovered, current conductors disposed laterally on the armature's rim, distributor and collector rings 35 respectively connected with the opposite ends of said conductors, annular brushes in contact with said rings, and wire connections between said brushes and the terminals of the electric circuit.

21. A dynamo-electric machine comprising a field-magnet, a discoidal armature therein, distributor and collector rings on opposite sides of said armature, current conductors on the armature's rim, having their ends respectively connected with said rings, 45 brushes in contact with the latter, adjusting members for said brushes, and means exerting a yielding pressure on said adjusting members.

22. A dynamo-electric machine comprising a field-magnet, a discoidal armature arranged to revolve therein, distributor and collector rings carried on opposite sides of said armature, current conductors on the armature's rim having their opposite ends connected with said rings, annular brushes 55 respectively in contact with the distributor rings and the collector rings and independently adjustable with relation to the same, suspending means attached to said brushes, 60 and spring-pressed adjusting members en-

gaged by said suspending means and operating to urge the brushes individually against the rings.

23. A dynamo-electric machine comprising a field-magnet, a discoidal armature 70 therein, distributor and collector rings on opposite sides of said armature, current conductors on the armature's rim having their opposite ends respectively connected with said rings, brushes in contact with the latter, 75 said brushes being provided with external projections, longitudinally movable tubular members engaging said projections, and means normally pressing said tubular members inward.

24. A dynamo-electric machine comprising an annular field-magnet, a discoidal armature mounted to revolve therein, current conductors disposed laterally on the armature's rim, current distributors and current 80 collectors on both sides of the armature respectively connected with the opposite ends of said conductors, brushes in contact with said distributors and said collectors, adjusting members for said brushes slidably supported on opposite sides of the field-magnet, tensioning devices adjacent to said adjusting members, and means whereby the adjusting members are brought under the influence 85 of said devices.

25. A dynamo-electric machine comprising a field-magnet, a discoidal armature therein, distributor and collector rings on opposite sides of said armature, current conductors on the armature's rim having their 90 opposite ends connected with said rings, paired brushes in contact with the latter, adjusting members for the several brushes 95 slidably toward and away from the field-magnet, spirally wound tensioning devices projecting outwardly from opposite sides of the field-magnet and wrapped around said adjusting members, and means connected with said devices whereby the adjusting members can be moved endwise.

26. A dynamo-electric machine comprising an annular field-magnet, a discoidal armature mounted to revolve therein, current conductors disposed laterally on the armature's rim, pairs of current distributors and 100 of current collectors on the opposite sides of the armature respectively connected with the opposite ends of said conductors, paired brushes in contact with said distributors and said collectors, terminal rods following the 105 curvature of the field magnet and wires respectively connecting the paired brushes with said terminal rods.

27. A dynamo-electric machine comprising an annular field-magnet formed with 115 opposed polar surfaces and a recess outwardly located with relation to the latter, a discoidal armature having an uncovered central portion and a rim projected between said surfaces, current conductors laterally 120

disposed on said rim, current distributers at the inner ends of said conductors bordering the uncovered portion of said armature, current collectors at the outer ends of the conductors within said recess, and brushes arranged to contact respectively with said distributers and said collectors.

In testimony whereof, I have signed my name to this specification, in the presence of two subscribing witnesses.

ALBERT A. E. STERZING.
